UNITED STATES PATENT OFFICE.

ASBURY G. WILSON, OF WILKINSBURG, PENNSYLVANIA.

SYSTEM FOR CHARGING STORAGE-CELLS.

No. 827,836.

Specification of Letters Patent.

Patented Aug. 7, 1906.

Application filed January 13, 1906. Serial No. 295,860.

To all whom it may concern:

Be it known that I, ASBURY G. WILSON, a citizen of the United States, residing at Wilkinsburg, in the county of Allegheny and State of Pennsylvania, have invented certain new and useful Improvements in Systems for Charging Storage-Cells, of which the following is a specification.

My invention relates to systems for charging a plurality of storage or secondary cells from a common source of current-supply, and provides means for alternately charging and discharging the cells and of interchanging the functions thereof in such a manner that while one cell or set of cells is being charged another set may take its place in the discharging-circuit to which the first-mentioned set was previously assigned.

My invention is particularly applicable to systems used in connection with railway-signals.

I will describe a system embodying my invention and will then point out the novel features thereof in claims.

In describing my invention I will refer specifically to a system in which twelve cells are divided into three sets of four cells each and will show how by the use of the circuits and apparatus embodying my invention any one of the three sets of cells may be placed in circuit with the battery-charging line while the other two sets are employed in discharging their current through the various translating devices—such as motors, relays, &c.—which it is desired to operate.

Figure 1 is a side elevation of a switch which I prefer to use for the control of the circuits embodying my invention. Fig. 2 is a plan view of Fig. 1. Figs. 3, 4, 5, and 6 are diagrammatic views illustrating four different ways in which the various cells may be connected with the charging and discharging circuits by the use of my system.

Although the switch shown in Figs. 1 and 2 is of the type I prefer to use in connection with the system I shall herein describe, I do not necessarily limit myself to its use, as any switch of a different construction but performing the same functions might be used in its stead.

Referring to Figs. 1 and 2, the switch A is made up of two double-pole double-throw switches A' and A², and each of the said double-pole switches A' and A² is composed of two single-pole switches, (designated a' a² and

a³ a⁴, respectively.) The two switches a' a² are connected together by a bar a⁵, of wood, fiber, rubber, or other insulating material, and the two switches a³ a⁴ are in like manner connected together by the bar a⁶. The two bars a⁵ and a⁶ are likewise connected together by the bar a⁷. Suitable binding-posts or equivalent means are provided for connecting the external circuits to the switch blades and jaws. The contact-blades of the switches a' a² a³ a⁴ are preferably constructed of bronze or brass and are adapted to move into and out of contact with their respective contact-jaws a⁸ a⁹ a¹⁰ a¹¹ a¹² a¹³ a¹⁴ a¹⁵.

In Figs. 3, 4, 5, and 6 I have shown a diagrammatic view of switch A. B, C, D, and E designate double-pole double-throw switches of like construction to A, and F is any suitable type of double-pole double-throw switch for connecting the switch E with the charging-circuit. All of the aforementioned switches may be mounted on a common switchboard, and I provide means for operating the four switches A B C D simultaneously, so that when the contacts at a⁸, a⁹, a¹², and a¹³, for example, are closed the corresponding contacts of switches B, C, and D will also be closed and when the aforementioned contacts of switch A are open the corresponding contacts of B, C, and D will be open. The switch E is adapted to be moved independently of the switches A, B, C, and D and may therefore occupy a like position to that of the said four switches, as in Figs. 4 and 6, or an unlike position, as in Figs. 3 and 5.

k' k² k³ k⁴ and l' l² l³ l⁴ designate single storage or secondary cells, and m designates four storage-cells connected together in series, all of the said k, l, and m cells being of the same size and capacity. One pole of the cell k' is connected to the contact-jaws a⁸ and a¹⁴ of the switch A, the said two jaws being connected in multiple, and the other pole of the same cell is connected to the jaws a⁹ and a¹⁵. In like manner one pole of k² is connected to the contact-jaws b⁸ and b¹⁴ of switch B and the other pole to the jaws b⁹ and b¹⁵. The cell k³ is connected in a like manner to the corresponding contact-jaws of switch C and the cell k⁴ to the corresponding jaws of switch D. It will be seen that the contact-jaws a¹⁰ and a¹² are electrically connected together, as are contacts a¹¹ and a¹³, and that one pole of cell l' is connected to the said contacts a¹⁰ and a¹² and the other pole to a¹¹ and a¹³. The cell

l^2 is connected in a like manner to the corresponding contact-jaws of switch B and the cells l^3 and l^4 to the corresponding contacts of switches C and D, respectively. The contact-blades a^3 and a^4 of switch A are connected, respectively, to the two sides or arms of an external circuit comprising one or more translating devices R' . In the accompanying drawings I have shown R' in the form of a relay device adapted to respond in the movement of its armature r' to the presence or absence in its coils of current derived from cell k' or l' , as the case may be. In like manner the contact-blades b^3 and b^4 of switch B are connected to an external circuit comprising the translating device R^2 . c^3 and c^4 are connected to a circuit comprising R^3 , and d^3 and d^4 to a circuit comprising R^4 . The battery of four cells, which I have designated m , is connected as to one pole to the contacts e^8 and e^{14} of switch E, the other pole being connected to the contacts e^9 and e^{15} . The contact-jaws e^{10} and e^{12} are connected by the wire or other conductor 11 to the contact-blade d^2 of switch D, and e^{11} and e^{13} are connected by the conductor 8 to the contact-blade a^2 of switch A. The two contact-blades e' and e^2 of switch E are connected, respectively, to the two jaws f' and f^2 of switch F. The jaw a^2 of switch A is connected to the jaw b' of switch B. b^2 in like manner is connected to c' , and c^2 to d' . The wires 10 and 9, leading from the contact-blades e^3 and e^4 , respectively, of switch E, form part of a circuit which comprises one or more translating devices. In the accompanying drawings I have shown four such translating devices S' , S^2 , S^3 , and S^4 , which may for convenience be regarded as motors, and these motors, as I will hereinafter show, are adapted to derive current for their operation from the four cells in battery m or from $k' k^2 k^3 k^4$ in series or from $l' l^2 l^3 l^4$ in series, according to the position in which the switches A, B, C, D, and E are set. J designates a source of current-supply which provides the energy for charging the various cells hereinbefore described, and j' j^2 are wires or conductors conveying current from the said source to the switch F. The switch F is cut into circuit with the wire j' , as shown, and, if desired, a plurality of switches, such as F, may be cut into circuit on the same line j' in series with F, and a plurality of battery-charging systems such as I am describing may be fed therefrom. When it is not desired to charge any of the cells k' , &c., l' , &c., or m , the switch F may be thrown over onto contacts j^3 and j^4 , which are electrically connected, and the charging-line j' thereby kept closed.

I will now describe the operation of my system and will show how each set of cells in turn may be placed in circuit with the charging-line and how either the k set or the l set of cells may be connected to feed the circuit

comprising the motors while the m set of cells is being charged, and, furthermore, how when the m cells are feeding the motor-circuit either of the other two sets of cells may be used to feed the circuits comprising the relays.

Referring to Fig. 3 and starting from the source J, current flows from said source through wire j' , thence through one blade of switch F, wire 1 to contact-blade e' of switch E, jaw e^8 , wire 2, wire 3, battery of cells m , wire 4, wire 5, jaw e^9 , blade e^2 , wire 6, thence through the other blade of switch F and continues along line j' to the point of connection of said line with return conductor or line j^2 , and so back to the other pole of the source J, whence it started. While the cells m are thus in circuit with the charging-line, the circuit comprising the translating devices S' S^2 S^3 S^4 must be fed from some other source of current-supply. With the switches A, B, C, and D in the position shown in Fig. 3 the said circuit will be fed from the cells $l' l^2 l^3 l^4$, and the path of the current may be traced as follows: Starting from one pole of cell l' , the current flows through wire 7, contact-jaw a^{10} , switch-blade a' , wire 8, jaw e^{13} of switch E, e^4 , wire 9, through the translating devices S' S^2 , &c., in parallel circuit, wire 10, e^3 , e^{12} , wire 11, d^2 , d^{11} , wire 12, cell l^4 , wire 13, d^{10} , d^9 , wire 14, c^2 , c^{11} , wire 15, cell l^3 , wire 16, e^{10} , e^9 , wire 17, b^2 , b^{11} , wire 18, cell l^2 , wire 19, b^{10} , b^9 , wire 20, a^2 , a^{11} , wire 21 back to the other pole of cell l' , from which it started. It will be seen that in the circuit I have just described all the four cells $l' l^2 l^3 l^4$ are included and that they are in series. Consequently the same voltage is available at the terminals of the translating devices S' S^2 , &c., as was supplied by the four m cells. While the m cells are thus being charged and the l cells are taking their place as a source of current-supply for S' S^2 , &c., the four k cells are respectively feeding the four circuits containing the translating devices R' R^2 R^3 R^4 . For example, the circuit of R' may be traced from one pole of k' through wire 22, a^{14} , a^3 , wire 23, translating device R' , wire 24, a^4 , a^{15} , and wire 25 back to the other pole of k' . In like manner the circuit of R^2 may be traced from one pole of cell k^2 through wire 26, b^{14} , b^3 , wire 27, translating device R^2 , wire 28, b^4 , b^{15} , wire 29 to the other pole of k^2 . The circuit of R^3 starts from one pole of cell k^3 and continues through wire 30, c^{14} , c^3 , wire 31, translating device R^3 , wire 32, c^4 , c^{15} , wire 33 back to the other pole of k^3 . In like manner the cell k^4 feeds the circuit of translating device R^4 .

Fig. 4 shows a different arrangement of circuits to that illustrated in Fig. 3. The switch E occupies the same position as before and the m cells are still connected to the charging-circuit and are receiving current from the source J. The other switches, how-

ever, A, B, C, and D have been thrown into their other position, so that the four k cells are now connected up in series to feed the circuit comprising the translating devices 5 $S' S^2 S^3 S^4$, and the four cells $l' l^2 l^3 l^4$ are now connected up individually and respectively to the four circuits comprising $R' R^2 R^3 R^4$. The circuit which is now fed by the k cells may be traced as follows: Starting from one 10 pole of k' , the current flows through wire 22, contact-jaw a^8 , blade a' , wire 8, jaw e^{13} of switch E, blade e^4 , wire 9, translating devices $S' S^2 S^3 S^4$, wire 10, e^3, e^{12} , wire 11, d^2, d^9 , wire 37, cell k^4 , wire 34, d^8, d^l , wire 14, c^2, c^9 , 15 wire 33, cell k^3 , wire 30, c^8, c' , wire 17, b^2, b^9 , wire 29, cell k^2 , wire 26, b^8, b' , wire 20, a^2, a^9 , wire 25 back to the other pole of cell k' . The circuit of R' may be traced from one pole of l' through wire $7, a^{12}, a^3$, wire 23, R' , wire 24, 20 a^4, a^{13} , wire 21 back to the other pole of l' . The circuit of R^2 starts from one side of l^2 through wire 19, b^{12}, b^3 , wire 27, R^2 , wire 28, b^4, b^{13} , wire 18 back to the other pole of l^2 . In like manner R^3 and R^4 are in circuit, respectively, with l^3 and l^4 , and these circuits being similar to those of R' and R^2 already described need not be traced out at length.

Fig. 5 illustrates another arrangement of circuits. In this view I have shown the 30 switches A, B, C, and D as occupying the same positions as in Fig. 4. The switch E, however, is not in the same position as in Fig. 4. Consequently the m cells are now disconnected from the charging-line j' and are instead placed in circuit with the translating devices $S' S^2 S^3 S^4$. This circuit may be traced as follows: from one pole of m through wire 3, e^{14}, e^3 , wire 10, through $S' S^2 S^3 S^4$ in multiple, wire 9, e^4, e^{15} , and wire 40 45 back to the other pole of m . The circuits of R', R^2, R^3 , and R^4 are fed from cells $l' l^2 l^3 l^4$, as in Fig. 4, in reference to which they have already been traced. The remaining circuit to be traced in Fig. 5 is the battery-charging 50 circuit, and this is as follows: Starting from one pole of the source of current supply J, the battery flows through wire j', f^3 , and f'' in switch F, wire 1, e', e^{10} , wire 11, d^2, d^9 , wire 37, cell k^4 , wire 34, d^8, d^l , wire 14, c^2, c^9 , wire 55 60 65 33, k^3 , wire 30, c^8, c' , wire 17, b^2, b^9 , wire 29, k^2 , wire 26, b^8, b' , wire 20, a^2, a^9 , wire 25, cell k' , wire 22, a^8, a' , wire 8, e^{11}, e^2 , wire 6, f^2, f^4 , in switch F, line j' , to end of line and then back on line j^2 to the other pole of source J, from whence it started.

Fig. 6 illustrates a fourth arrangement of circuits. In this case the cells m are in circuit with $S' S^2 S^3 S^4$, as in Fig. 5. The translating devices R', R^2, R^3, R^4 are in circuit, respectively, with the four cells $k' k^2 k^3 k^4$, as in Fig. 3, and the battery-charging line is in circuit with the cells $l' l^2 l^3 l^4$. This last circuit may be traced as follows: from source J through wire j', f^3 , and f'' in switch F, wire 1, 65 e', e^{10} , wire 11, d^2, d^{11} , wire 12, cell k^4 , wire 13,

d^{10}, d^l , wire 14, c^2, c^{11} , wire 15, b^3 , wire 16, c^{10} , c' , wire 17, b^2, b^{11} , wire 18, b^l , wire 19, b^{10}, b^l , wire 20, a^2, a^{11} , wire 21, b^l , wire 7, a^{10}, a' , wire 8, e^{11}, e^2 , wire 6, f^2 and f^4 of switch F, line-wire j' and back by line-wire j^2 to the other pole of source J.

From the foregoing description of the circuits illustrated in Figs. 3, 4, 5, and 6 it will be seen that by the use of my system any one of the three sets of cells, which I have designated $k', &c.$, $l', &c.$, and m , may be placed in circuit with the battery-charging source of supply J; also, that while the k set of cells is connected to the charging-circuit the l set of cells is feeding the circuits comprising R', R^2, R^3 , and R^4 and the m cells are supplying current to $S' S^2 S^3 S^4$. On the other hand, when the l set of cells is in circuit with the charging-line the k cells are in circuit with R', R^2, R^3 , and R^4 and the m cells are again feeding S' , and, finally, when m is being charged one of the two remaining sets k and l is supplying current to $S', &c.$, and the other is in circuit with $R', &c.$.

What I claim is—

1. In combination, a charging-circuit, two independent sets of storage-cells, translating devices supplied from either set of storage-cells, switches for connecting either set of storage-cells with the translating devices and simultaneously disconnecting the other set from the translating devices, and another switch and circuits for connecting the charging-circuit with the disconnected set of storage-cells, through the said switches, 90

2. In combination, two independent sets of storage-cells, translating devices supplied from either set of storage-cells, switches for connecting either set of storage-cells with the translating devices and simultaneously disconnecting the other set from the translating devices, other translating devices and another switch and circuits for connecting one of the two independent sets of cells with said other translating devices through the said first-mentioned switches, 105

3. In combination, a charging-circuit, two independent sets of storage-cells, translating devices supplied from either set of storage-cells, switches for connecting either set of storage-cells with the translating devices and simultaneously disconnecting the other set from the translating devices, other translating devices, a third set of storage-cells, and another switch and circuits for connecting either set of independent storage-cells through the first-mentioned set of switches with the charging-circuit and for connecting or disconnecting, through independent circuits the said third set of storage-cells with the said 115 other translating devices, 120

4. In combination, a charging-circuit, two independent sets of storage-cells, translating devices supplied from either set of storage-cells, switches for connecting either set of 130

storage-cells with the translating devices and simultaneously disconnecting the other set from the translating devices, other translating devices, a third set of storage-cells, and another switch and circuits for connecting one of the two independent sets of cells through the first-mentioned switches with said other translating devices, and for connecting and disconnecting said third-men-

tioned set of storage-cells with the charging- 10 circuit.

In testimony whereof I have signed my name to this specification in the presence of two subscribed witnesses.

ASBURY G. WILSON.
